US0D1103758S

(12) **United States Design Patent** (10) **Patent No.:** **US D1,103,758 S**
(45) **Date of Patent:** **** Dec. 2, 2025**

(54) **FOOD PACKAGING**

(71) Applicant: **Kellanova**, Battle Creek, MI (US)

(72) Inventor: **Eric Patrick Lewandowski**, Grand Ledge, MI (US)

(73) Assignee: **KELLANOVA**, Battle Creek, MI (US)

(**) Term: **15 Years**

(21) Appl. No.: **29/895,729**

(22) Filed: **Jun. 26, 2023**

Related U.S. Application Data

(62) Division of application No. 29/744,777, filed on Jul. 31, 2020, now Pat. No. Des. 1,009,620, which is a division of application No. 29/666,134, filed on Oct. 10, 2018, now Pat. No. Des. 894,731.

(57) **CLAIM**

The ornamental design for a food packaging, as shown and described.

DESCRIPTION

The FIGURE is a food packaging, showing my new design. The broken lines in the FIGURE illustrate the portions of the food packaging and form no part of the claimed design. The long-broken lines in the FIGURE are included to show claimed perforation lines on the article.

The claim is directed to the perforation lines only.

1 Claim, 1 Drawing Sheet
